AIRPLANE

Ronald A. Duryea, Clearwater, Fla.
(423 Country Club Drive, Oldsmar, Fla. 33557)

Filed May 7, 1973, Ser. No. 357,637

Term of patent 14 years

Int. Cl. D12—07

U.S. Cl. D12—71

FIG. 1

FIG. 2

FIG. 4

FIG. 3

FIG. 5

FIG. 1 is an elevational view of one side of an airplane showing my new design; said one side and the opposite side of said airplane being identical in appearance.

FIG. 2 is an elevational view of the front of said airplane.

FIG. 3 is an elevational view of the rear of said airplane.

FIG. 4 is a top plan view of said airplane.

FIG. 5 is a bottom plan view of said airplane.

I claim:
The ornamental design for an airplane, as shown and described.
